REMOTE CONTROL APPARATUS

Earl M. Allen and Charles A. Brooks, Swissvale, Pa., assignors to The Union Switch & Signal Company, Swissvale, Pa., a corporation of Pennsylvania

Application February 17, 1930. Serial No. 428,966
Renewed March 27, 1931

29 Claims. (Cl. 246—134)

Our invention relates to remote control apparatus, and has for an object the provision of novel and improved apparatus for controlling railway traffic governing devices such as switches and signals from a distant point.

We will describe one form of apparatus embodying our invention, and will then point out the novel features thereof in claims.

The accompanying drawing is a diagrammatic view showing one form of apparatus embodying our invention.

Referring to the drawing, the reference characters 1 and 1^a designate the track rails of a stretch Y of railway track connected by means

15 of a switch G with a stretch Z. Portions of stretches Y and Z adjacent switch G are divided by means of insulated joints 2 to form track sections A—B, C—D, B—E—D and E—F. Each of these sections is provided with a track circuit 20 which includes a battery 3 connected across the rails adjacent one end of the section, and a track relay designated by the reference character T with a distinguishing exponent and connected across the rails adjacent the opposite end of the section.

25 Signals designated by the reference characters S^{1a}, S^{1b}, S^{1c} and S^{1d} govern eastbound traffic moves, that is, moves toward the right as shown in the drawing, over switch G, and signals S^{2a}, S^{2b} and S^{2c} govern westbound moves over switch G. Signals S^{1a}, S^{1b}, S^{2a} and S^{2c} govern moves over switch G in its normal position as shown, for directing traffic along stretch Y only. Signals S^{1c}, S^{1d}, S^{2b} and S^{2c} govern moves over switch G reversed, from or to stretch Z, respectively. As shown in the drawing, each of these signals is of the semaphore type. Each of the signals operates a contact arm which connects with a given terminal when the signal is indicating "stop", and which connects with a second terminal when the signal is indicating "proceed". For example, signal S^{1a} operates contact arm 35 which connects with terminal 35^a when signal S^{1a} is indicating stop, and which connects with terminal 35^b when signal S^{1a} is indicating proceed.

35 Switch G, as here shown, is operated by a fluid pressure motor M which is controlled by a lock magnet L and by normal and reverse magnets N and R, respectively. These magnets are, in turn, controlled by a polarized switch relay H^G and by a polarized switch indication relay K^G as well as by traffic conditions and by signals S. Magnets N and R jointly control armature 95 which, when magnet N is energized, swings contact arms 20 and 63 to the left, as shown in the drawing, and

which, when magnet R is energized, swings these contact arms to the right.

Operated in conjunction with switch G are contact arms 21 and 27 which connect with terminals 21^a and 27^a, respectively, when and only when switch G is in its normal position. Contacts 21—21^b, 27—27^b and 65 are closed at all times except while switch G is in its normal position. Contacts 62—62^b, 61—61^b and 64, also operated in conjunction with switch G, are closed at all times except while switch G is in its reverse position. Contacts 62—62^a and 61—61^a are closed when and only when switch G is in its reverse position.

Switch relay H^G is energizable in the normal 70 or the reverse direction by a circuit which is controlled by a manually operable lever V^G. Lever V^G has two positions, a normal position n and a reverse position r. A contact arm 5, operated by lever V^G, connects with terminal 5^a when lever V^G is in its n position, and connects with a terminal 5^b when lever V^G is in its r position. A contact arm 29, also operated by lever V^G, connects with a terminal 29^a when lever V^G is in its n position, and connects with a terminal 29^b when lever V^G is in its r position.

Switch indication relay K^G is controlled by contact arms 20 and 63 which are operated by magnets N and R, and is also controlled by the contact arms which are operated in conjunction with switch G, and by switch relay H^G. If the control circuit for relay H^G is energized while relay K^G is deenergized, relay H^G responds, but the resistance of the circuit is great enough to prevent the flow of sufficient current to operate an indication relay h^G which is in series with relay H^G and which is shown adjacent lever V^G. When motor M responds to control by relay H^G and moves switch G to a corresponding position, relay K^G becomes energized in a direction which corresponds with the position of switch G and with the direction of energization of relay H^G.

Relay K^G, upon becoming energized, forms a shunt path around a resistance 9 in the circuit for relay H^G and also around a portion of the winding of relay H^G, thus permitting sufficient current to flow in the circuit to operate relay h^G and at the same time to retain the contacts of relay H^G in an energized position.

Normal and reverse switch indication relays 105 kⁿ and k^r are energized when relay K^G is energized in the normal or the reverse direction, respectively.

Signals S are controlled by a polarized signal relay H^S. One of the signals S¹ or one of the 110

signals S^2 will be controlled by relay H^s according as relay H^s is energized in the reverse or the normal direction, respectively. A stop signal indication relay K^{S1} is energized when and only when all of the signals S^1 are indicating stop. A second stop signal indication relay K^{S2} is similarly energized when and only when all signals S^2 are indicating stop. A proceed signal indication relay K^s is energized when and only when any one of the signals S^1 or S^2 is indicating proceed. A signal stick relay I is controlled by stop signal indication relays K^{S1} and K^{S2} and by track relay T^3 .

An approach locking stick relay U^1 is controlled by traffic conditions as well as by stop signal indication relay K^{S1} and by a manually operable contact P^1 . An approach locking stick relay U^2 is similarly controlled by traffic conditions as well as by stop signal indication relay K^{S2} and by a manually operable contact P^2 .

The energization of relay H^s in the normal or the reverse direction is controlled by a manually operable lever V^s having a normal position m , a reverse position to the left f , and a reverse position to the right t . The lever V^s operates a contact arm 70 which, when the lever is in its f position, connects with a terminal 70^a, and when the lever is in its t position, connects with a terminal 70^b. A contact arm 93, also operated by lever V^s , similarly connects with a terminal 93^a when lever V^s is in its f position, and connects with a terminal 93^b when the lever is in its t position.

If the circuit for relay H^s is energized while proceed signal indication relay K^s is deenergized, relay H^s will respond, but the current flowing will be insufficient to operate a second proceed signal indication relay h^s which is connected in series with relay H^s . Upon the clearing of a signal due to the energization of relay H^s , relay K^s becomes energized. Relay K^s , upon becoming energized, forms a shunt path around a resistance 67 which is in series with relays h^s and H^s . This shunt path also passes around a portion of the winding of relay H^s . With the resistance of the circuit thus reduced, sufficient current will flow to operate relay h^s as well as to retain the contacts of relay H^s in an energized position.

Indicators, here shown as electric lamps each of which is designated by the reference character e with a distinguishing exponent, are placed adjacent levers V^G and V^s for the information of the operator. Lamp e^T is controlled by a back contact of relay h^G and, when lighted, at times indicates that track section B—E—D is occupied. Lamp e^T , when lighted during an operation of switch G from one position to the other, indicates that the movement of switch G has not yet been completed in response to a change of position of lever V^G . Lamps e^n and e^r are controlled by contacts 29—29^a and 29—29^b, respectively, of lever V^G as well as by a front contact of relay h^G . Lamp e^n , when lighted, indicates that switch G is in the normal position while lever V^G is in its n position, and lamp e^r indicates that switch G is in the reverse position while lever V^G is in its r position. Lamp e^m is controlled by a back contact of relay h^s and, when lighted, indicates that none of the signals is indicating proceed although lever V^s has been moved to its f or t position. Lamps e^f and e^t are controlled by contacts 93—93^a and 93—93^b, respectively, of lever V^s , and by a front contact of relay h^s . Lamp e^f , when lighted, indicates that one of the signals S^2 , controlled by lever V^s when in its f position, is indicating proceed. Lamp e^t ,

when lighted, indicates that one of the signals S^1 , controlled by lever V^s when in its t position, is indicating proceed.

A signal call-on control relay W has a pick-up circuit which is controllable by a manually operable contact, here shown as a push button contact P^{Vs} , when stop signal indication relays K^{S1} and K^{S2} are energized. Relay W has a stick circuit which includes a portion of the circuit for relay H^s comprising relay h^s , contact 70—70^a or 70—70^b of lever V^s , and a battery Q^3 or a battery Q^4 , respectively.

As here shown, batteries Q^3 and Q^4 also supply energy for lighting indicator lamps e . Current for controlling the local circuits for switch G and signals S is supplied by a battery Q^1 and a battery Q^2 .

In the drawing, the contacts operated by the various relays are identified by numbers, such numbers having suitable distinguishable exponents when such contacts are not shown adjacent the respective relays by which they are operated. The exponent for each of these contact numbers comprises the reference character and exponent for the respective relay. For example, the exponent K^{S2} , for contact 73 K^{S2} shown in the local control circuits for signals S^1 , comprises the reference character K and the exponent S^2 for stop signal indication relay K^{S2} which operates contact 73 K^{S2} . Similarly, the exponent W for contact 89 W in the local circuit for signal S^{1b} comprises the reference character W for call-on relay W which operates contact 89 W .

Having thus described, in general, the arrangement, operation, and location of the various parts comprising our invention, we will now trace in detail the operation of the apparatus.

As shown in the drawing, all parts are in their normal condition, that is, lever V^G is in its n position, lever V^s is in its m position, switch G is in its normal position, all signals are indicating stop, and all track sections are clear.

With signals S^1 indicating stop, stop signal indication relay K^{S1} is energized by its circuit passing from terminal x^2 of battery Q^2 , through contacts 35—35^a, 36—36^a, 37—37^a, and 38—38^a of signals S^{1a} , S^{1b} , S^{1c} and S^{1d} , respectively, and the winding of relay K^{S1} to the other terminal o of battery Q^2 . With signals S^2 indicating stop, stop signal indication relay K^{S2} is energized by its circuit passing from terminal x^2 , through contacts 39—39^a, 40—40^a, and 41—41^a of signals S^{2a} , S^{2b} and S^{2c} , respectively, and the winding of relay K^{S2} to terminal o .

With relays T^1 and T^2 energized, approach locking relay U^1 is energized by its circuit passing from terminal x^2 , through contact 46 of relay T^1 , contact 47 of relay T^2 , and the winding of relay U^1 to terminal o . A stick circuit for relay U^1 is also completed, passing from terminals x^2 , through contact 48 of relay K^{S1} , contact 51 of relay U^1 , and the winding of relay U^1 to terminal o . With relay T^4 energized, approach locking relay U^2 is energized by its circuit passing from terminal x^2 , through contact 52 of relay T^4 , and the winding of relay U^2 to terminal o . A stick circuit for relay U^2 is also completed, passing from terminal x^2 , through contact 53 of relay K^{S2} , contact 57 of relay U^2 , and the winding of relay U^2 to terminal o .

With relays T^3 , K^{S1} and K^{S2} energized, the pick-up circuit for relay I is completed, passing from terminal x^2 , through contact 42 of relay T^3 , contact 43 of relay K^{S1} , contact 44 of relay K^{S2} , and the winding of relay I to terminal o . A stick

circuit for relay I is also completed, passing from terminal x^2 , through contact 42 of relay T³, contact 45 of relay I, and the winding of relay I to terminal o.

5 With lever V^G in the n position, relay H^G is energized in the normal direction by a circuit passing from battery Q³, through wire 4, contact 5^a—5 of lever V^G winding of relay h^G, wire 6, contact 7T³, wire 10, contact 11 of relay K^G, wire 12, a portion of the winding of relay H^G, and wires 13^b and 13^a back to battery Q³. With relay H^G energized in the normal direction and with relays I, U¹ and U² energized, normal magnet N for switch G is energized by its circuit passing 80 from terminal x^1 of battery Q¹, through front contacts 14¹, 15U¹ and 16U², contacts 17 and 18^b of relay H^G, wire 19, the winding of magnet N to terminal o, and through battery Q² back to battery Q¹. With magnet N energized and with relay H^G energized in the normal direction, as well as with switch G in the normal position, relay K^G is energized in the normal direction by its circuit passing from terminal x^2 of battery Q², through contact 20^a—20 operated by magnet N, contact 21^a—21 of switch G, contacts 22^a and 23 of relay H^G, winding of relay K^G, contacts 24 and 25^a of relay H^G, wire 26, and contact 27—27^a of switch G to terminal o. With relay K^G energized in the normal direction, normal indication relay kⁿ is energized by its circuit passing from terminal x^2 , through contacts 33 and 34^a of relay K^G, and the winding of relay kⁿ to terminal o.

On account of relay K^G being energized and thus forming, by its contact 11, a shunt path around resistance 9 and a portion of the winding of relay H^G, the resistance of the circuit for relay H^G is reduced and so permits sufficient current to flow to operate relay h^G. With relay h^G thus energized, lamp e^r is lighted by its circuit passing from battery Q⁴, through wire 13^a, lamp e^r, wire 28, contact 29^a—29 of lever V^G, and contact 30^a of relay h^G back to battery Q⁴.

The circuit for relays h^s and H^s is open at contact arm 70 of lever V^s, and hence both these relays are deenergized.

We will now assume that the operator desires to arrange for a train to move from stretch Z to stretch Y over switch G reversed. He therefore moves lever V^G to the r position, and lever V^s to the t position. Lever V^G, upon being moved from the n position toward the r position, breaks, at its contact 5^a—5, the circuits for relays h^G and H^G. Relay H^G, upon becoming deenergized, opens its contacts 23 and 24, causing relay K^G to be deenergized and open its contact 11.

When lever V^G reaches its r position, relays h^G and H^G will be energized in the reverse direction by a circuit passing from battery Q⁴, through wires 13^a and 13^b, winding of relay H^G, resistance 9, wire 8, contact 7T³, wire 6, winding of relay h^G, and contact 5—5^b of lever V^G back to battery Q⁴. Relay H^G, upon becoming energized in the reverse direction, completes a shunt circuit for relay K^G passing from relay K^G, through contacts 23 and 22^b of relay H^G, contacts 62—62^b and 61—61 of switch G, and contacts 25^b and 24 of relay H^G back to relay K^G. This shunt circuit insures that relay K^G will become deenergized even though the circuit first traced for relays h^G and H^G should be supplied with current of reverse polarity before relay K^G has opened its contact 11.

With relay H^G energized in the reverse direction, a circuit is completed for magnet R of switch G, passing from terminal x^1 of battery Q¹,

through front contacts 14¹, 15U¹ and 16U², contacts 17 and 18^b of relay H^G, wire 58, and the winding of magnet R to terminal o. With relay K^G deenergized, a circuit for lock magnet L is also completed, passing from terminal x^1 of battery Q¹, 80 through contact 59 of relay K^G, wire 60, and the winding of magnet L to terminal o. With magnets L and R thus energized, motor M is so controlled as to move switch G to the reverse position.

Upon the beginning of the operation of switch G, contact arms 21 and 27 are moved to connect with terminals 21^b and 27^b, respectively, and contact 65 is closed. With contact 65 closed, a second circuit is completed for magnet L, passing from terminal x^1 of battery Q¹, through contacts 64 and 65 of switch G, wire 60, and the winding of magnet L to terminal o. Upon the completion of the operation of switch G to its reverse position, contact arms 62 and 61 are moved to connect with terminals 62^a and 61^a, 95 respectively, and contact 64 is opened.

On account of magnet R being energized, armature 95 has moved contact arms 20 and 63 to connect with terminals 20^b and 63^b, respectively, and hence when contact arms 62 and 61 100 are moved as just described, a reverse control circuit is completed for relay K^G, passing from terminal x^2 , through contact 61^a—61 of switch G, contacts 25^b and 24 of relay H^G, winding of relay K^G, contacts 23 and 22^b of relay H^G, contact 62—62^a of switch G, and contact 63—63^b of magnet R to terminal o. Relay K^G, upon becoming energized, again completes, through its contact 11, the shunt path previously traced around resistance 9 and a portion of the winding 105 of relay H^G. Upon the completion of this shunt path, sufficient current flows through the circuit for relays h^G and H^G to cause relay h^G to again become energized.

While relay h^G has been deenergized, lamp e^r 115 has been lighted by its circuit passing from battery Q⁴, through wire 13^a, lamp e^r, and contact 30^b of relay h^G back to battery Q⁴. Lamp e^r, while thus lighted, has been indicating to the leverman that switch G has not yet completed 120 its movement to the reverse position. Upon the reenergization of relay h^G as just described, lamp e^r becomes extinguished, and lamp e^r becomes lighted by its circuit passing from battery Q⁴, through wire 13^a, lamp e^r, contact 29^b—29 of 125 lever V^G, and contact 30^a of relay h^G back to battery Q⁴. With lamp e^r lighted, the operator knows that switch G has been moved to the reverse position in response to the movement of lever V^G to its r position.

Relay K^G, being energized in the reverse direction, completes the circuit for relay k^r, passing from terminal x^2 of battery Q², through contacts 33 and 34^b of relay K^G, and the winding of relay k^r to terminal o.

130 Lever V^s having been moved to its t position, battery Q⁴ supplies current of reverse polarity to relays h^s and H^s by a circuit passing from battery Q⁴, through wires 13^a, 13^b, 13^c and 13^d, winding of relay H^s, resistance 67, wires 69 and 69^a, winding of relay h^s, and contact 70—70^b of lever V^s back to battery Q⁴. Relay H^s responds by closing its contacts 71 and 72^b, but the current flowing in the circuit is not sufficient 140 to cause relay h^s to open its back contact 31^b and close its front contact 31^a. With contact 31^b closed while lever V^s is in its t position, lamp e^m is lighted by its circuit passing from battery Q⁴, through wire 13^a, lamp e^m, wire 32, contact 150

31^b of relay h^s , and contact 70—70^b of lever V^s back to battery Q^4 .

With relay H^s energized in the reverse direction as just described, and with relay k^r energized, a circuit is completed for signal S^{1c} , passing from terminal x^2 of battery Q^2 , through contacts 71 and 72^b of relay H^s , contacts 73^{ks2}, 74^{kr}, 75^I, 76^{T4}, and the mechanism of signal S^{1c} to terminal o . The arm of signal S^{1c} now moves to terminal o . The arm of signal S^{1c} now moves to terminal o .

Relay K^s , upon becoming energized, completes a shunt path for the circuit already traced for relays H^s and h^s , passing from a connection within the winding of relay H^s , through contact 68 of relay K^s to wire 69. This shunt path, by passing around resistance 67 and a portion of the winding of relay H^s , reduces the resistance in the circuit for relays h^s and H^s , and so permits sufficient current to flow through the circuit to cause relay h^s to open its back contact 31^b and close its front contact 31^a. Upon the opening of contact 31^b, lamp e^m becomes extinguished, and upon the closing of contact 31^a, lamp e^t becomes lighted by its circuit passing from battery Q^3 , through wire 4^a, contact 31^a of relay h^s , contact 93—93^b of lever V^s , lamp e^t , and wire 13^a back to battery Q^3 . With lamp e^t lighted, the operator knows that the arm of signal S^{1c} has been operated to the proceed position in response to the movement of lever V^s to its t position and the operation of switch G to its reverse position.

We will now assume that an eastbound train approaching signal S^{1c} deenergizes relay T^2 . The stick circuit already traced for relay U^1 has been broken at contact 48 upon the deenergization of relay K^{S1} , and hence, upon the deenergization of relay T^2 which causes its contact 47 to open in the pick-up circuit previously traced for relay U^1 , relay U^1 becomes deenergized. Relay U^1 , upon becoming deenergized, breaks, at the front point of its contact 15^{U1}, the circuit previously traced for magnet R of switch G , and completes at the back point of its contact 15^{U1} a second circuit for magnet R passing from terminal x^1 of battery Q^1 , through front contact 14^I, back contact 15^{U1}, contact 94^b of relay K^G , wire 58, and the winding of magnet R to terminal o . It follows that with relay U^1 deenergized, the position of switch G can not be influenced by a change in direction of the energization of relay H^G .

As the train proceeds past signal S^{1c} , it deenergizes relay T^3 , causing relay I to be deenergized. Relay I , upon becoming deenergized, breaks, at its front contact 14^I, the second circuit just traced for magnet R , and completes, at its back contact 14^I, a third circuit for magnet R , which is the same as the second circuit except passing through the back contact 14^I instead of through the front contact 14^I and back contact 15^{U1}. It follows, therefore, that while relay I is deenergized, switch G will not be influenced by any change in the direction of energization of relay H^G . Relay I , upon becoming deenergized, also opens its contact 75^I in the circuit previously traced for signal S^{1c} . The arm of signal S^{1c} thereupon moves to its stop position, breaking, at its contact 37—37^b, the circuit for relay K^s , and then completing, at its contact

37—37^a, the circuit previously traced for relay K^{S1} .

Relay K^s , upon becoming deenergized, opens, at its contact 68, the shunt path previously traced around resistance 67 and a portion of the winding of relay H^s . The current flowing in the circuit of relays h^s and H^s is thereby so reduced as to cause relay h^s to open its front contact 31^a and close its back contact 31^b. Lamp e^t is thus extinguished, and lamp e^m is again light as previously described, indicating to the operator that the arm of signal S^{1c} has left its proceed position.

The circuit for relays h^G and H^G is open at contact 77^T, causing relay h^G to become deenergized and extinguish lamp e^r and then light lamp e^T . The lighting of lamp e^T now indicates to the operator that a train has entered section B—E—D. Relay H^G is also deenergized, causing relay K^G to be deenergized and to again complete the circuit for lock magnet L through contact 59 of relay K^G . With relay K^G deenergized, relay k^r is deenergized due to the opening of contact 33 of relay K^G .

The train, upon entering section E—F while relay T^3 is deenergized, completes, at contact 50 of relay T^4 , a second pick-up circuit for relay U^1 , passing from terminal x^2 of battery Q^2 , through contact 48 of relay K^{S1} , contact 49 of relay T^3 , contact 50 of relay T^4 , and the winding of relay U^1 to terminal o . A pick-up circuit commonly employed for an approach locking relay such, for example, as relay U^1 , includes a back contact of only one track relay, as, for example, relay T^3 . In our invention, however, the corresponding pick-up circuit for a relay such as relay U^1 , includes back contacts of two track relays in series as, for example, contacts 49 and 50 of relays T^3 and T^4 , respectively, in the second pick-up circuit which we have traced for relay U^1 . The use of back contacts of two track relays in series instead of a back contact of only one track relay prevents the possibility of a relay such as relay U^1 becoming energized by an incorrect momentary shunting of a single relay such as relay T^3 .

When the train leaves section B—E—D, relay T^3 becomes energized, completing at its contact 77^T, the circuit for relays h^G and H^G . Relay K^G then again becomes energized, completing the shunt path previously traced around resistance 9 and a portion of the winding of relay H^G . Relay h^G thereupon opens its contact 30^b, extinguishing lamp e^T , and then closes its contact 30^a, lighting lamp e^r . The operator is thereby informed that the train has left section B—E—D. When the train moves out of section B—E—D, relay I becomes energized by its pick-up circuit previously traced.

When the train leaves section E—F, the circuit previously traced for the arm of signal S^{1c} is again completed at contact 76^{T4}, causing the arm of signal S^{1c} to move to the proceed position. All parts of the apparatus will now again attain the same condition as before the train entered section C—D while signal S^{1c} was indicating proceed.

We will now assume that another train enters section C—D, deenergizing relay U^1 as previously described in connection with the first train. We will further assume that before the train passes signal S^{1c} , the operator decides to hold the train at signal S^{1c} and to arrange the apparatus for a third train to move along stretch Y over switch G in the normal position. The operator

therefore returns lever V^s to its m position, thereby breaking the circuit for relays h^s and H^s . Relay H^s is thereby deenergized, causing the arm of signal S^{1c} to return to the stop position. A trainman will then, upon instructions from the operator, close contact P^1 , thereby completing a third pick-up circuit for relay U^1 passing from terminal r^2 , through contact 48 of relay K^{s1} , contact P^1 , and the winding of relay U^1 to terminal o . With relay U^1 energized, the operator can, by returning lever V^g to its n position, cause the circuit previously traced for magnet N to be again completed and the circuit first traced for magnet L through contact 59 of relay K^g to also be completed. Switch G will thereupon be returned to its normal position.

We will next assume that switch G has been again reversed as previously described, and that the arm of signal S^{1c} has been moved to its proceed position. We will further assume that an eastbound train has passed signal S^{1c} , and that, before the train has passed out of section $E-F$, the operator desires to permit a following train to pass signal S^{1c} . On account of relay T^3 or relay T^4 being deenergized, the arm of signal S^{1c} is now in its stop position, and hence relay K^{s1} is energized. The operator will depress push button P^{vs} , thereby completing a pick-up circuit for relay W , passing from battery Q^4 , through wires 13^a , 13^b and 13^c , winding of relay W , contacts 87^{KS2} and 86^{KS1} , push button P^{vs} , contact 31^b of relay h^s , and contact $70-70^b$ of lever V^s back to battery Q^4 . Relay W , upon becoming energized, completes its stick circuit passing from battery Q^4 , through wires 13^a , 13^b and 13^c , winding of relay W , contact 88 of relay W , wire 69^a , winding of relay h^s , and contact $70-70^b$ of lever V^s back to battery Q^4 . With relay W energized, a circuit is completed for signal S^{1d} , passing from terminal r^2 of battery Q^2 , through contacts 71 and 72^b of relay H^s , contacts 73^{KS2} , 74^{kr} and 90^W , and the mechanism of signal S^{1d} to terminal o . The arm of signal S^{1d} is thereupon moved to its proceed position.

We have described for a few typical conditions the operation of the apparatus comprising our invention. Following this description, the operation of the apparatus for every other possible condition will be readily understood by reference to the drawing.

It will be noted from the foregoing that, in apparatus comprising our invention, a light is constantly displayed when switch F occupies its normal position except while section $B-E-D$ is occupied, and that a second light is constantly displayed when switch F occupies its reverse position except while section $B-E-D$ is occupied. It will also be noted that a light is constantly displayed when any one of the eastbound signals is indicating proceed, and that a second light will be constantly displayed when any one of the westbound signals is indicating proceed.

Although we have herein shown and described only one form of remote control apparatus embodying our invention, it is understood that various changes and modifications may be made therein within the scope of the appended claims without departing from the spirit and scope of our invention.

Having thus described our invention, what we claim is:

1. In combination, an electro-responsive device, a control circuit for said device, an indica-

tion means responsive only to current of greater magnitude than the current necessary for controlling said device, and means controlled by said device for reducing the resistance in said circuit to permit sufficient current to flow for controlling said indication means as well as said device. 80

2. In combination, an electro-responsive device, a control circuit for said device, an indication means responsive only to current of greater magnitude than the current necessary for putting said device into a given condition, and means controlled by said device for reducing the resistance in said circuit to permit sufficient current to flow for controlling said indication means as well as for continuing said device in said condition. 85

3. In combination, a railway traffic governing device, a relay for controlling said device, an indication means responsive only to current of greater magnitude than is necessary for operating said relay, a circuit for said relay and said indication means, and means controlled by said traffic governing device for removing a portion of the winding of said relay from said circuit 100 to permit current to flow for controlling said indication means as well as for retaining the contact of said relay in the same position as before. 95

4. In combination, a railway traffic governing device, a pair of conductors, means for at times supplying said conductors with current for controlling an operation of said device, an indication means, and means controlled by said governing device for increasing the current supplied to said conductors to cause said indication means to display a constant indication of the condition of 110 said device. 105

5. In combination, an electro-responsive device, an indication means, a control circuit for said device and said indication means, means for 115 supplying said circuit with current to which said device but not said indication means responds, and means controlled by said device for supplying said circuit with current to which said indication means as well as said device responds. 120

6. In combination, an electro-responsive device, an indication means, a control circuit for said device and said indication means, means for supplying said circuit with current to which said device but not said indication means responds, 125 and means controlled by said device when said device has responded to said current for supplying said circuit with current to which said indication means as well as said device responds. 130

7. In combination, a railway track switch, a polarized switch relay for controlling operations of said switch to the normal or the reverse position according as said relay is energized in the normal or the reverse direction, an indication means, a control circuit for said relay and said indication 135 means, means for supplying said current with current of normal or reverse polarity to which said switch relay but not said indication means responds, and means controlled by said switch for supplying said circuit with current to which said indication means as well as said switch relay responds. 140

8. In combination, a railway track switch, a polarized switch relay for controlling operations of said switch to the normal or the reverse position according as said relay is energized in the normal or the reverse direction, an indication means, a control circuit for said relay and said indication 145 means, means for supplying said circuit with current of normal or reverse polarity to which said 150

- switch relay but not said indication means responds, an indication relay energized when and only when said switch occupies a position corresponding to the direction of energization of said switch relay, and means controlled by said indication relay for supplying said circuit with current to which said indication means as well as said switch relay responds.
9. In combination, a railway track switch, a polarized indication relay controlled by said switch, and means controlled by polar contacts of said relay for at times retaining said switch in the position to which said switch has last previously been operated.
10. In combination, a railway track switch, a control means for said switch, a polarized indication relay energized when and only when said switch occupies one or the other extreme position corresponding to a condition of said control means respectively, and means controlled by polar contacts of said indication relay for at times retaining said switch in the position to which said switch has last previously been operated.
11. In combination, a railway track switch, manually operable means for controlling the switch, an indication relay controlled by said switch, and means controlled by said indication relay according to traffic conditions for controlling said switch independently of said manually operable means.
12. In combination, a railway track switch, manually operable means for controlling the switch, an indication relay controlled by said switch, a signal for governing traffic movements over said switch, and means controlled by said indication relay according to the condition of said signal for controlling said switch independently of said manually operable means.
13. In combination, a railway signal, a control means for said signal, an indication means, means for supplying said control means and said indication means with current to which said control means but not said indication means responds, and means controlled by said signal for supplying said control means and said indication means with current to which said indication means as well as said control means responds.
14. In combination, a railway track switch, manually operable means for controlling the switch, an indication means controlled by said switch, a signal for governing traffic movements over said switch, and means controlled by said signal according to the condition of said indication means for controlling said switch independently of said manually operable means.
15. In combination, a railway track switch, manually operable means for controlling said switch, an indication means controlled by said switch, and means controlled by traffic conditions according to the condition of said indication means for controlling said switch independently of said manually operable means.
16. In combination, a railway track switch, operating mechanism for said switch comprising a normal and a reverse magnet as well as a lock magnet, a control circuit for said switch, a polarized indication relay energized in the normal or the reverse direction according as said switch is in its normal or its reverse position when and only when said circuit is energized in the normal or the reverse direction respectively, a circuit for said lock magnet controlled by a back neutral contact of said indication relay, a circuit for said normal magnet controlled by a normal polar contact of said indication relay, and a circuit for said reverse magnet controlled by a reverse polar contact of said relay.
17. In combination, a railway signal, a signal relay for controlling said signal, a control circuit for said relay, a call-on control relay for said signal, a manually controlled pick-up circuit for said call-on relay, and a stick circuit for said call-on relay comprising the control circuit for said signal relay.
18. In combination, a railway signal, a signal relay for controlling said signal, a control circuit for said relay, a call-on control relay for said signal, a pick-up circuit for said call-on relay, and a stick circuit for said call-on relay comprising the control circuit for said signal relay.
19. In combination, a railway signal, an approach track circuit for said signal including a track relay, a second and a third track circuit each of which includes a track relay, an approach locking relay, a circuit for said approach locking relay controlled by said approach track relay, and a second circuit for said approach locking relay including a back contact of said second track relay in series with a back contact of said third track relay and controlled by said signal.
20. In combination, a railway signal, an approach track circuit for said signal including a track relay, a second and a third track circuit each of which includes a track relay, an approach locking stick relay, a pick-up circuit for said approach locking relay controlled by said approach track relay, a second pick-up circuit for said approach locking relay including a back contact of said second track relay in series with a back contact of said third track relay, and a stick circuit for said approach locking relay controlled by said signal.
21. In combination, a railway track switch, a normal control device for said switch, a reverse control device for said switch, a normal control circuit controlled by said normal control device, a reverse control circuit controlled by said reverse control device, a normal indication contact so controlled by said switch as to become closed when the switch is moved to its normal position, a reverse indication contact so controlled by said switch as to become closed when the switch is moved to its reverse position, means for at times transferring the control of said normal control circuit from said normal control device to said normal indication contact, means for at times transferring the control of said reverse control circuit from said reverse control device to said reverse indication contact, and means controlled by said normal and reverse control circuits for controlling operations of said switch to its normal and reverse positions respectively.
22. In combination, a stretch of railway track containing a switch, a polarized switch relay, a normal control circuit controlled by a normal contact of said switch relay, a reverse control circuit controlled by a reverse contact of said switch relay, a polarized indication relay controlled by said switch, means controlled by track circuit conditions in said stretch for at times transferring the control of said normal control circuit from the normal contact of said switch relay to a normal contact of said indication relay and for at times transferring the control of said reverse control circuit from the reverse contact of said switch relay to a reverse contact of said indication relay, and means controlled by said normal and reverse control circuits for controlling operations of said switch to its normal and reverse positions respectively.

DISCLAIMER

1,929,047.—*Earl M. Allen and Charles A. Brooks, Swissvale, Pa.* REMOTE CONTROL APPARATUS. Patent dated October 3, 1933. Disclaimer filed March 15, 1935, by the assignee, *The Union Switch & Signal Company*.
Hereby disclaims the subject matter of claims 19, 20, and 27.
